UNITED STATES PATENT OFFICE

116,767

DESIGN FOR A DISPLAY RACK

Russel W. Smith, Des Moines, Iowa

Application May 15, 1939, Serial No. 85,005

Term of patent 7 years

To whom it may concern:

Be it known that I, Russel W. Smith, a citizen of the United States and resident of Des Moines, Polk County, Iowa, have invented a new, original, and ornamental Design for a Display Rack, of which the following is a specification, reference being had to the accompanying drawing, forming a part thereof.

Fig. 1 is a front perspective view of a display rack showing my new design; and

Fig. 2 is a side elevational view thereof.

Fig. 3 is a vertical mid-sectional view of the display rack.

The rear of the display rack is the same as the front.

I claim:

The ornamental design for a display rack, substantially as shown and described.

RUSSEL W. SMITH.
